UNITED STATES PATENT OFFICE.

CYRUS CHAMBERS, JR., OF PHILADELPHIA, PENNSYLVANIA.

CLAY TEMPERING AND EXPRESSING DEVICE FOR BRICK-MACHINES.

SPECIFICATION forming part of Letters Patent No. 297,675, dated April 29, 1884.

Application filed December 26, 1883. (No model.)

To all whom it may concern:

Be it known that I, CYRUS CHAMBERS, Jr., a citizen of the United States, residing at the city and county of Philadelphia, and State of Pennsylvania, have invented certain new and useful Improvements in Clay Tempering and Expressing Devices for Brick-Machines, of which the following is a full, clear, and exact description, reference being had to the accompanying drawings.

Figure 1 is a side elevation of the tempering-knife shaft and the conoidal expressing-screw on the end of the same, all the knives save the first three adjacent to the screw having been removed. Fig. 2 is a front end view of the said shaft with all the knives in position, the screw having been taken off. Fig. 3 is a view of the screw detached, looking at its rear end, or that next to the shaft. Figs. 4 and 5 are diagrams illustrative of a certain difference between my present and previous arrangements of the tempering-knives upon the shaft.

This invention is an improvement in devices for a like purpose that have been used in the brick-machines patented to me by various Letters Patent of the United States—such as No. 207,343, of August 27, 1878, and No. 275,467, of April 10, 1883, and other patents previous to the foregoing for brick-machines—which have gone largely into use, and have been well known for some twenty years last past as the “Chambers Machine.”

The object of the invention is to improve the operation of said tempering and expressing devices through a new arrangement of the tempering-knives with relation to each other and to the expressing-screw.

The invention also consists in a more convenient mode of fitting the screw upon the end of the knife-shaft.

As shown in both of said patents, the knives are arranged around the pugging-shaft in a spiral winding in a direction opposite to that of the spiral of the screw. The special advantages of that arrangement of the knives are recited at the bottom of page 2 and top of page 3 of the specification of the patent of August 27, 1878, and I retain that relative arrangement of the spirals in the present device.

A reference to Fig. 1 of the drawings accompanying said Letters Patent will show that the knives constituting the successive turns of the spiral are arranged upon the shaft, as taken longitudinally, in a series of straight lines—that is to say, the arrangement is such that if a series of lines be drawn from one end of the shaft to the other through the longitudinal rows of knives each of these lines will touch a knife in every turn of the spiral—while by my present improved arrangement the knives are “staggered”—that is to say, if similar longitudinal lines be drawn as those just mentioned, they will touch a knife only in every alternate turn of their spiral.

A comparison of the diagrams, Figs. 4 and 5 of the drawings hereunto annexed, will show the difference between the old and the new arrangements, respectively. The small dots or circles therein represent the knives, the lines *e d* the spiral, and lines *a b* those drawn longitudinally with the shaft through the knives.

It will be observed that in Fig. 4 the lines *a b* touch a knife in each turn of the spiral, while in Fig. 5 they touch only knives in alternate turns. The latter construction is further shown by Fig. 2, wherein the knives (twenty-seven in number) are numbered in succession, following the curve of the spiral around shaft A, beginning with the knife (1) nearest the screw, and ending with the one (27) at the other extremity of the shaft.

The advantage resulting from this arrangement consists in the securing of a comparatively greater space between the knives upon the longitudinal lines, and yet have quite as many, and, in fact, more, knives as heretofore upon the shaft. Thus the clay between the knives has ample room, the amount of friction is diminished, and the clay is prevented from liability of lodging between the knives.

Referring now to Fig. 1, it will be seen that the knife marked 1—that is, the first knife of the spiral—is placed as on a continuation of the spiral flange of the screw S, some distance beyond the latter; also, that the knife 2 is located to the left and in advance of the end of the screw-flange, about half-way between the latter and the knife 1, and that a considerable lateral space is left between said knife 2 and the screw. By this relative arrangement of

these two knives and the rear end of the screw, sufficient space is left between the first knife and the opposite side or flange of the screw for the clay advanced by said knife to enter 5 between it and the screw, and ample space is left between the second knife and the mouth of the screw for the body or furrow of clay advanced by both the first and second knives to easily enter the mouth of the screw without 10 undue packing or jamming of the clay.

In order to insure the connection of the screw to the end of the knife-shaft always in the one proper position with relation to these adjacent knives, I provide the socket C in the 15 rear end of the screw with unequidistant projections or lugs b' , Fig. 3—three in number in the present instance. These lugs coincide with grooves b in the forward end of shaft A, into which the former enter when the screw is 20 forced upon the shaft until stopped by the shoulder thereon. The grooves and lugs are of course located in the suitable relative positions for securing the desired result. In this way the screw will be rotated by and with the 25 shaft, and it will be impossible for an error to be made in placing the screw in position.

I claim—

1. In combination with the shaft and screw, the knives arranged upon said shaft in a spiral running reversely to the spiral of the screw 30 and staggered longitudinally, in the manner and for the purpose specified.

2. In combination with the screw and the knives arranged on the shaft in the manner shown, the first two knives located with relation to each other and the screw, as and for the purpose specified. 35

3. In combination with the knives and their shaft provided with the unequidistant end grooves, the screw having the socket, with 40 lugs corresponding to said grooves, substantially as and for the purpose specified.

4. In combination with the pugging-shaft, the tempering-knives arranged thereon in a spiral, and staggered, as and for the purpose 45 specified.

In testimony whereof I have hereunto affixed my signature this 18th day of December, A. D. 1883.

CYRUS CHAMBERS, JR.
